ELECTRIC BROILER FOR HAMBURGERS AND LIKE ARTICLES

Frank Schatten, Beechurst, N. Y., and Thomas Alderdice,
New Milford, N. J.

Application January 27, 1956, Serial No. 39,948

Term of patent 14 years

(Cl. D81—10)

We claim:

The ornamental design for an electric broiler for hamburgers and like articles, substantially as shown.
